(57) CLAIM

The ornamental design for a plate, as shown and described.

DESCRIPTION

FIG. 1 is a front, perspective view of a plate showing our new design;

FIG. 2 is a front view thereof;

FIG. 3 is a rear view thereof;

FIG. 4 is a right side view thereof, the left side view being a mirror image to the right side view;

FIG. 5 is a top view thereof; and,

FIG. 6 is a bottom view.

The features shown in broken lines portions of the plate forming no part of the claimed design. The features shown in long dash-short dash bolded broken lines indicate the bounds of the claimed design and otherwise form no part of the claimed design.

1 Claim, 4 Drawing Sheets(56)
